FILTER BAG

Carl E. Meyerhoefer, Little Neck, N. Y., assignor to Lewyt Corporation, Long Island City, N. Y., a corporation of New York

Original application April 22, 1954, Serial No. 424,887, now Patent No. 2,792,076, dated May 14, 1957. Divided and this application March 8, 1957, Serial No. 644,771

1 Claim. (Cl. 183—51)

This invention relates to a structurally and functionally improved filter bag and especially a unit intended for use in connection with vacuum cleaners; the present invention also teaching a novel combination of filter bag structure and such vacuum cleaners.

The present application is a division of my earlier application for patent, Serial No. 424,887 on Filter Bag, filed in the U. S. Patent Office on April 22, 1954, now Patent No. 2,792,076.

It is an object of the invention to furnish a unit of this type by means of which penetration of its body or wall by the high velocity impingement of dirt particles thereagainst, will be prevented.

Still another object is that of designing a filter which will be less susceptible to weakening and rupturing than heretofore and which may be economically manufactured by quantity production machinery and methods at less cost than air-pervious bags as heretofore designed.

With these and other objects in mind, reference is had to the attached sheet of drawings illustrating practical embodiments of the invention and in which:

Fig. 1 is a sectional side view taken through a portion of a vacuum cleaner assembly and showing one form of the present filter bag in association therewith;

Fig. 2 is a face view of that bag;

Fig. 3 is a perspective view of the completed bag, with a portion of the same broken away to disclose underlying construction; and

Fig. 4 is a somewhat diagrammatic view showing an alternative structure.

Referring primarily to Fig. 1, the numeral 10 indicates the upper casing portion of a vacuum cleaner assembly which is closed by a lid 11 conveniently mounted by a hinge (not shown). Disposed within this lid is a disk-type filter 12 of air pervious material. The general construction involved is substantially identical with that disclosed in United States Patent 2,716,465, dated August 30, 1955.

As taught in that patent, the upper casing portion 10 encloses an imperforate trough having an open upper face and side walls 13 spaced from the inner face of the casing walls. Due to the spacing, passages for the flow of air are present. The base of this trough, as indicated at 14, may include an upwardly bulged or pedestal portion. Below this, a motor blower unit 15 is disposed.

As also disclosed in the prior patent, a coupling for a hose 16 is provided in association with casing portion 10. The latter mounts in line with the opening defined by this collar or coupling, a deflector shield 17, the base of which may be circular in section and the inner end of which terminates in a downwardly and inwardly opening hood. A bag of air-porous paper is disposed within trough 13 and includes a body 18. The latter is formed with an opening adjacent its forward end and which opening is defined by a collar 19. This collar encircles the fitting or inlet unit 17 in the manner shown in Fig. 1.

Under these circumstances, and with the motor blower unit 15 operating, dust-laden air will be drawn through

2

the hose coupling and deflector 17 into the interior of the bag 18. Therefore, as indicated, dust-laden particles will be directed against the inner face of the base portion or lower surface of the bag as shown in this figure.

5 In that area, the bag is supported by the upwardly bulged part 14 of the trough, if such structure be included in the assembly. The air will distend the bag so that it substantially fills the trough with its rear end braced against the adjacent surface of the latter and its upper surface bearing against parts of the filter assembly 12.

Even if the base portion of the trough be corrugated, a minimum amount of filtered air will pass through the adjacent bag wall, although the latter be formed of air-porous paper. Rather, the greatest amount of the air

15 will move upwardly through the bag in the direction of filter 12. Thereupon, it will pass through the bag wall and the filter assembly 12 and reverse its course to flow between the inner face of casing section 10 and trough 13 toward the motor blower unit. From the latter, it

20 will be discharged through a suitable outlet or outlets as disclosed in my prior patent. It is found that in the case of air-porous paper providing the surface against which the dust particles impinge upon their entrance into the bag and due to the velocity of particle movement

25 they are forced through the paper. This will occur throughout the area indicated by the flow lines in Fig. 1. Upon the bag being filled and removed, the adjacent base portion 14 of the trough will be covered with such particles.

30 By means of the present teachings, this objectionable result is avoided. More particularly and as shown in Figs. 2 and 3, the outer end of the bag may be defined by a square area 20, centrally of which collar 19 is mounted by having its flange glued or otherwise secured

35 adjacent the bag opening. The side walls 21 of the bag extend from the rectangular end thereof and terminate in a base portion 22, within which there may be incorporated a suitable number of folds 23 to provide a seal at this point. The side walls 21 include an upper part 21a and a lower part 21b. All of these parts are generally manufactured of air-pervious paper with the exception only of collar 19.

However, as shown in Figs. 1 to 3, a layer 24 of relatively hard, abrasion-resisting material is applied to the inner face of one of the side walls 21, with its end edges spaced from the base 22 and the outer end 20. This layer is preferably formed of air-impervious paper and is secured in position by glue. Specifically it may be made of kraft paper, which embodies the desired characteristics and which costs only a fraction per pound of air-pervious paper, providing the remainder of the bag body.

The material of the outer bag end 20 is preferably continued within the area defined by collar 19. A slit, or transverse line of weakening 26 extends across this space. 55 Arcuate slits, or weakening lines 27 are also provided extending from the line 26, adjacent the inner collar surface through to points short of each other to furnish flaps 25 permanently connected to the bag body by what might be termed "hinge portions."

60 It follows as a consequence of this structure, the application of the bag to the fixture or deflector 17, will result in the end wall of the bag opening along the lines of weakening 26 and 27. In effect, flaps 25 will thus be furnished which remain integrally united with the bag body. The collar 19 and its associated flange being wholly outside of the bag, it is apparent that they will not interfere with the hinging or swinging action of the flaps. Accordingly, no interference with incoming dust-laden air will occur incident to the use of these flaps—70 which when the bag is mounted—will be swung to wholly open positions. However, with cover 11 swung up

wardly, the bag may be removed by simply withdrawing collar 19 over the fixture 17. With that action, air and the mass of foreign material (dust, dirt particles, etc.) will be subjected to a slight compressive action resulting in the flaps shifting outwardly to positions at which they are substantially co-extensive with the outer end 20. Thus, they will function as a check valve structure to prevent an escape of dust and dirt particles from the bag interior as the latter is removed from trough 13 and subsequently disposed of.

It will be observed in connection with the strip of impervious material that the bag is mounted within the trough to have this strip lie in contact with the base portion 14 of that unit, with a fixture or deflector 17 of the type shown and described. Therefore, incoming air laden with foreign material will be deflected downwardly onto the surface of strip 24. The particles of foreign material will, under these circumstances, simply rebound from the surface of that strip. Due to the character of the latter, no impingement between these particles and the strip will occur such that the dust particles are forced through or into the paper. At the same time, the filtering action of the bag will not be impaired because the amount of air normally passing between its lower surface (when in applied position) and the base 14 of the trough is of minimum volume. It follows that when the bag is removed from the trough, the latter will be left in completely clean condition with no dirt discoloration appearing on the inner surface of the trough base.

As will be understood by those conversant with bag-making machines, the cost of manufacture in applying a separate strip 24 to be incorporated in the body of the bag will not, in effect, be increased over a bag in which all side walls are of the same gauge and material and integral with each other. However, the cost of material such as kraft paper is only fractional in comparison with proper air-porous paper. Therefore, with a large quantity of bags involved, the over-all cost of manufacture will be materially reduced. The same results of lack of penetration of the bag body by dirt particles may, of course, be achieved by constructions other than that illustrated in Figs. 1, 2 and 3.

For example, if in lieu of the deflector 17, a fitting such as 28 is employed—as in Fig. 4—a discharge of the dirt-laden air will occur into the bag along the path indicated in that figure. As shown this will be towards the inner face of the base portion of that receptacle. Where such a path is involved, that area of the bag need not include a fold zone 23 of the nature shown in the earlier figures. Rather, the base may be defined by a simple overlap of the adjacent terminal areas 29 and 30 of the bag base. The facing surfaces of these layers may be adhesively secured to each other. Whether they are, or not, they will be overlain by a layer 31 of material corresponding to layer 24. So disposed and secured to parts 29 and 30

by adhesive, layer 31 will serve to maintain those parts against separation. Obviously, it will protect them from perforation or damage by contact with abrasive particles.

It is preferred that layer 24 or 31 be sufficiently thin to be quite flexible. In this manner it will not prevent the bag from being rolled up, or folded to assume a compact configuration for purposes of storage or packaging. The layer—in every instance—will be in face-to-face contact with the adjacent surface of the air-porous paper and the intervening adhesive may extend throughout the entire area of contact.

Thus, among others, the several objects of the invention as specifically aforesaid are achieved. Obviously numerous changes in construction and rearrangements of the parts might be resorted to without departing from the spirit of the invention as defined by the claim.

I claim:

For use with a vacuum cleaner having a compartment defined by a rigid wall to accommodate and support a filter bag to be discarded after it has once been filled with dust and similar material, a bag including a body formed of air-pervious paper of single thickness throughout at least the major portion of the bag body, said body having side walls formed of said paper, said side walls including an upper part and a lower part, a layer of air-impervious kraft paper overlying a portion of the inner face of said lower part, said layer being more resistant to abrasion by said dust and similar material than said air-pervious paper, said layer being adhesively secured to said body in substantially face-to-face contact, the inner confines of said bag as defined by said body being substantially free from any obstructing means except said layer, a substantially rectangular outer end and base forming a part of said bag and separated from each other by said side walls, said layer having end edges spaced from said outer end, the base of said bag including a zone having edge portions secured against separation from each other, a collar having an opening therethrough and extending laterally from said outer end, said outer end having zones thereof cooperable to provide a pair of integrally hinged flaps adjacent said collar and normally closing the collar opening and further being pivotable away from each other to a position within the confines of said bag as defined by said body, and each of said hinged flaps being formed of said air-pervious paper and having an axis and further being pivotable away from the other of said flaps about its axis, and the axis of each of said flaps being disposed substantially normal to said lower part of said side walls.
